PORTABLE LANTERN

William H. Jones, Raytown, Mo., assignor to William H. Jones Sporting Goods Mfg. Co., Inc., Raytown, Mo., a corporation of Missouri

Filed Sept. 19, 1960, Ser. No. 62,184

Term of patent 14 years

(Cl. D48—24)

FIG. 1 is a top plan view of a portable lantern, showing my new design;

FIG. 2 is a side elevational view thereof;

FIG. 3 is a front elevational view thereof;

FIG. 4 is a rear elevational view thereof; and

FIG. 5 is a vertical cross-sectional view taken on the line 5—5 of FIG. 2 of my design.

The bottom of the portable lantern is plain and the side not shown is substantially the same in appearance as the side shown.

I claim:

The ornamental design for a portable lantern, as shown and described.
